UNITED STATES PATENT OFFICE.

JASPER L. PEPPER, OF BUTLER, INDIANA.

SPARK-ARRESTER.

No. 839,193.

Specification of Letters Patent.

Patented Dec. 25, 1906.

Application filed April 30, 1906. Serial No. 314,342.

To all whom it may concern:

Be it known that I, JASPER L. PEPPER, a citizen of the United States, residing at Butler, in the county of Dekalb, in the State of Indiana, have invented certain new and useful Improvements in Spark-Arresters; and I do hereby declare that the following is a full, clear, and exact description of the invention, which will enable others skilled in the art to which it appertains to make and use the same, reference being had to the accompanying drawings, which form part of this specification.

My invention relates to improvements in spark-arresters for steam-engines specially designed and adapted for traction-engines.

It is well known that the attempt to prevent the destructive effects of escaping sparks from the smoke-stack of steam-engines, particularly of traction-engines for threshing and the like, by means of spark-arresting screens has not been either satisfactory or successful, for the reason that when the meshes of the screens are sufficiently fine to properly arrest the smaller sparks the draft of the smoke-stack is seriously impaired, and when the screens are sufficiently coarse to permit a proper draft the smaller sparks and ignited cinders escape in large quantities and frequently cause destructive conflagrations.

The object, therefore, of my present invention is to provide a cheap, simple, reliable, and efficient spark-arrester for either stationary or locomotive engines arranged within the boiler-shell in such a coöperative relation with the forward end of the boiler-tubes and the base of the smoke-stack as to permit a free and unobstructed draft, while at the same time substantially all live sparks are arrested and deposited in the spark-box of the extension-front of the boiler.

My invention consists of a novel arrangement of deflectors or baffle-plates in the extension-front or spark-box of the engine-boiler in coöperative relation with the discharge end of the boiler-flues and beneath the lower end of the smoke-stack and adapted to direct the sparks to a receiving-compartment, where they are securely retained, instead of being permitted to escape through the smoke-stack.

The principal novel feature of my invention resides in the construction and coöperative arrangement of the baffle-plates by which the sparks are directed to and deposited in the retaining-compartment.

Similar reference-numerals in the accom-

panying drawings indicate like parts in both the views, in which—

Figure 1 is a side elevation of the forward end of the steam-engine boiler, partly in longitudinal central section, showing the relative arrangement of the deflecting baffle-plates, also in vertical section. Fig. 2 is a front end elevation of the same with the end door of the boiler removed and the annular strengthening-flange partly broken away to show the manner of securing the baffle-plates at their ends.

My invention is shown mounted in the extension-front of the tubular-boiler shell 1 of a common form of engine, the boiler having a common arrangement of boiler-tubes 2 with their forward ends secured, as usual, in the transverse flue-sheet 3. The extension-front has a proper boiler-head door 4 and the usual exhaust-pipe 5 and nozzle 6 communicating directly with and discharging into the lower end of the smoke-stack 7 for the usual well-understood purpose.

At a proper point in the boiler extension-front and to the opposite sides thereof are rigidly fixed a plurality of upright plates 8, to whose inner face are rigidly fixed the transverse baffle-plates 9, having diverging sides of proper length and having their apex pointing rearwardly, as shown. These plates have their adjacent sides slightly separated to form throughout their length narrow transverse openings 10, to which the live sparks as they are projected from the adjacent ends of the boiler-tubes 2 are deflected by the inclined sides of the said plates and through which openings the sparks pass into the compartment or chamber 11, where they are deposited and retained. Directly beneath the lower edge of the lowest of these baffle-plates is arranged the forward edge of the concave shield or plate 18, whose rear end is rigidly fixed to the flue-sheet 3 just below the lower tier of the boiler-tubes, and whose forward end is so arranged below the lower baffle-plate as to leave a suitable transverse spark-opening 12 of substantially the same width as the openings 10. At a proper point in the extension-front and slightly forward of and above these baffle-plates 9 is rigidly fixed 100 a pendent transverse plate 13, having its lower edge provided with a rearwardly-extended concavo-convex transverse deflector-plate 14, adapted to arrest such sparks as 110 might escape upward at that point into the smoke-stack and deflect them into the de-

posit-chamber 11. To the flue-sheet 3 at a point above the boiler-flues and approximately in about the same plane as the uppermost of the said baffle-plates is rigidly fixed 5 a transverse horizontal deflector-plate 15, whose forward edge has a slight downward curve portion 16, whose forward edge is arranged in such a coöperative relation with the rear edge of the deflector 14 that all sparks 10 from the flues which have a tendency to fly upward to the rear of the deflector 14 are arrested and directed forward to the baffle-plate openings, as before described. The plate 15 may be further braced, strengthened, and secured by means of the cross-piece 17. The 15 openings between the adjacent edges of the deflectors 14 and 16 and between the deflector 14 and the adjacent baffle-plate 9 are of proper width.

20 The operation of my invention thus described is obvious and, briefly stated, is as follows: All such sparks as are projected downward are deflected forwardly by the plate 18 and directed through the opening 12 into the 25 settling or deposit chamber 11. All sparks from the flues which are projected upwardly are arrested either by the deflector 16 or the opposite deflector 14, the two adjacent edges thereof being so arranged as to perform that 30 function and at the same time leave a sufficient transverse opening to permit the smoke and gases of combustion to freely escape upward to the smoke-stack 7. The vertical side of the cross-piece 17 is preferably of sufficient height to aid in promptly directing 35 the exhaust and the lighter products of combustion to the lower end of the smoke-stack. It is thus evident that all the sparks of appreciable size and weight to hold fire even for 40 a moment will be directed and deflected directly into the deposit-chamber 11 by means of the baffle-plates 9, the deflectors 14 and 16, and the plate 18.

Having thus described my invention and the manner of employing the same, what I 45 desire to secure by Letters Patent is—

1. A spark-arrester fixed in the forward extension of a boiler-shell, and consisting of a series of V-shaped baffle-plates in vertical arrangement, having their apices rearwardly 50 pointing and being separated by transverse openings as described; a pair of deflector-plates in coöperative arrangement with the upper one of said baffle-plates, and with each other; and a deflecting-plate in coöperative 55 relation with the lower one of said plates.

2. A spark-arresting apparatus for the forward extension of a boiler-shell, consisting of a plurality of V-shaped baffle-plates in vertical alinement, and having their apices rearwardly pointing, and having their adjacent sides separated as shown at their forward edge; and means for directing the sparks to the baffle-plates without interfering with the escape of the smoke and gases of combustion. 65

3. In a spark-arrester for steam-engines the combination of a series of V-shaped baffle-plates in vertical arrangement having their apices rearward, and the forward adjacent edges of their sides separated to form transverse openings for the sparks; a curved deflector-plate above the said baffle-plates and in coöperative relation therewith; and a horizontally-arranged deflector-plate at the 70 rear of the said baffle-plates, and in coöperative relation with the said curved deflector-plate.

Signed by me at Butler, Dekalb county, State of Indiana, this 28th day of April, A. D. 8, 1906.

JASPER L. PEPPER.
